UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

ELECTRIC-CONDUCTOR SUPPORT AND SYSTEM.

1,402,000.

Specification of Letters Patent.

Patented Jan. 3, 1922.

Application filed September 2, 1921. Serial No. 498,119.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Elec-
tric-Conductor Supports and Systems, of
which the following is a specification.

My invention relates to trolley devices and
10 has particular reference to that class of de-
vices in which it is desired to suspend one
or more conductors from an overhead sup-
port.

It is very often desirable that the trolley
15 wire or wires shall be suspended or supported
from a catenary or messenger cable below
and to one side of the cable as in the case of
curve construction, and when such a con-
struction is used it is found that not only
20 the length but the angularity of the sup-
porting member extending between the con-
ductors and supporting cable must be varied,
and one object of my invention is to provide
a device whereby the angularity of the mem-
25 ber extending between the clamping member
for the conductors and the overhead support
may be varied relatively to the overhead sup-
port or the conductor clamp or both.

In the drawing accompanying this specifi-
30 cation—

Fig. 1 shows a front view of my inven-
tion as applied to two conductors, one of
which is a trolley wire or contact wire for a
35 collector and the other an auxiliary con-
ductor, both suspended from a supporting
or catenary cable.

Fig. 2 shows an end view of the device as
shown and used in Fig. 1.

In the construction shown in the accom-
40 panying drawing I have provided two clamp-
ing members 1 and 2 respectively, held to-
gether and in a clamping position by a
through-bolt 3. At the upper end of the
clamping members 1 and 2 is shown a T
45 shaped member 4 provided at one end with
a cross member 5 having on one surface
thereof serrations 6 engaging with similar
serrations 7 on the clamping member 1
and provided at the other end with screw-
50 threaded means 8 for the attachment of sup-
porting member 9. To the opposite end of
the supporting member 9 to which the mem-
ber 4 is secured, is an attachment 10 by
means of which the whole device is secured
55 to a catenary cable 11. The clamping mem-

bers 1 and 2 are provided at their lower edge
with jaws 12 and 13 respectively to engage
and grip a trolley conductor 14. The upper
end of the clamping member 2 is provided
with a jaw 15. The member 4 is provided 60
with a groove 17 co-acting with the jaw 15
to engage and grip the conductor 16.

The specific construction herein shown and
described offers a very compact arrange-
ment for freely suspending the two conduc-
tors to one side of the messenger cable in
combination with means for adjusting the
angularity of the supporting rod 9 with re-
spect to the conductors 14 and 16, such that
the conductors may assume a natural posi-
70 tion relatively to the catenary cable due to
any side and downward stress upon the con-
ductors. There are many modifications
which will readily suggest themselves and
be apparent to one skilled in the art and 75
which would fall within the scope of my in-
vention as set forth in the claims, and while
I have shown the means of adjustment lo-
cated at the upper end of the clamping mem-
bers and forming one groove 17 co-acting 80
with the jaw 15 to grip the upper conductor,
it is quite apparent that the adjusting mem-
ber 4 may readily be modified and located
elsewhere and co-act with the clamping mem-
bers 1 and 2 to suspend the clamping mem-
85 bers from the messenger cable 11 and permit
adjustability.

The installation of my invention will be
quite apparent as it is merely a matter of
causing the clamping members to grip the 90
two conductors, placing the member 9 at such
an angle as is believed to meet the require-
ments and tightening the parts up by means
of the bolt and nut 3—3' and then engaging
the member 10 with the catenary cable 11, 95
or the catenary cable 11 may be engaged first
by the member 10 and then the device se-
cured to the trolley conductors 14 and 16.

The parts shown in dotted lines in Fig. 2
indicate the adjustability of such parts with 100
respect to the clamping members 1 and 2.
In this position the one conductor is shown
in a direct horizontal line with respect to
the messenger cable.

While I have described my invention as 105
applied to two conductor cables, it will be
quite apparent also that the adjustable fea-
ture and its form of connection with the
clamping members or an equivalent arrange-
ment can be applied to a device designed to 110

suspend a single conductor and the device herein shown and described can be used on a single conductor 14 if desired, by merely inserting a substitute member of proper size and short length in place of the conductor

5 16. While I have shown the two conductors with their axes in a common vertical plane, my invention will permit of adjustment so that their axes will rest in a common plane
10 other than that of a vertical plane.

Having described my invention I claim:—

15 1. A support for a plurality of conductors comprising clamping means to maintain the conductors in a fixed relation to each other, connecting means associated and co-acting with the clamping means to secure the clamping means to a support and means coacting with the clamping and connecting means whereby the angularity of the connecting means relative to the clamping means may be varied.

20 2. A support for a trolley conductor comprising clamping means to grip the conductor, connecting means associated and coacting with the clamping means to secure the clamping means to a support and means coacting with the clamping and connecting means whereby the angularity of the connecting means relative to the clamping means may be varied.

25 3. A support for a plurality of conductors comprising clamping means to maintain the conductors in a fixed relation to each other, connecting means associated and co-acting with the clamping means to secure the clamping means to a support, means co-acting with the clamping and connecting means whereby the angularity of the connecting means relative to the clamping means may be varied, and means to clamp and hold the parts in a predetermined position relative to each other.

40 4. A support for a plurality of conductors comprising clamping means to maintain the conductors in a fixed relation to each other, connecting means associated and co-acting with the clamping means to secure the clamping means to a support and means co-acting with the clamping and connecting means whereby a line intersecting the axes of the conductors may be varied relatively to a line passing through one of the conductors and the support.

45 5. A support for a plurality of conductors comprising clamping means to maintain the conductors in a fixed relation to each other, connecting means adjustably associated and coacting with the clamping means to suspend the conductors from a support in an adjustable relation thereto, and means to clamp and hold the parts in a predetermined relation to each other.

60 6. A support for a plurality of conductors comprising clamping means to maintain the conductors in a fixed relation to each

other, a connecting member having means at one end to connect to a support and means at the other end for securing the connecting member to the clamping means in adjustable relation.

70 7. A support for a plurality of conductors comprising clamping means to maintain the conductors in a fixed relation to each other, a connecting member having means at one end to connect to a support, means at the other end for securing the connecting member to the clamping means in adjustable relation, and means to secure the clamping means and the connecting member in a predetermined fixed relation.

75 8. A support for a trolley conductor comprising clamping means to grip the conductor, a connecting member having means at one end to connect to a support and means at the other end for securing the connecting member to the clamping means in fixed relation thereto and permitting the fixed relation to be changed at will.

80 9. An overhead system for electric railways comprising a catenary cable, two conductors positioned below and to one side of the catenary cable and held together in a fixed relative position by clamping means, an inclined member having one end secured to the catenary cable and the other end adjustably secured to the clamping means such that the angle formed by the longitudinal axis of the inclined member and a line intersecting the axes of the conductors at the clamping means may be varied.

85 10. An overhead system for electric railways comprising a catenary cable, a conductor positioned below and to one side of the catenary cable, clamping means to engage and grip the conductor, an inclined member having one end secured to the catenary cable and the other end adjustably secured to the clamping means such that the inclination of the inclined rod may be varied and fixed at will in any desired position.

90 11. A support for a plurality of conductors comprising clamping means to maintain the conductors in a fixed relation to each other, a connecting member for suspending the clamping means from a support and adjustably secured to the clamping means whereby the angle formed by a line intersecting the axis of the conductors and the longitudinal axis of the connecting member may be varied.

95 12. A support for a plurality of conductors comprising clamping means to maintain the conductors in a fixed relation to each other, a connecting member having means for attachment to an overhead support and means for adjustable attachment to the clamping means with the longitudinal axis of the connecting member intersecting one of the conductors.

100 13. A support for a plurality of conduct-

- tors comprising a clamping means comprising a pair of members having at one end oppositely disposed jaws to grip a wire and having at the opposite end on one of the 5 members a jaw to engage a conductor and the other member having means to secure an adjustable member thereto; an adjustable member having means extending therefrom to engage an overhead support and oppositely disposed to the last mentioned jaw to receive the second conductor and to coact with the oppositely disposed jaw to grip the conductor, and means on the adjustable member coacting with means on the engaged 10 clamping member whereby the angular relation of the projecting means on the adjustable means may be varied; and means to move the clamping members and adjustable member into engagement with the conductors and lock the adjustable member in position relative to the clamping members. 15
14. A support for a plurality of conductors comprising clamping means to maintain the conductors in a fixed relation to each 20 other, the clamping means comprising a pair of clamping members, a connecting means associated and coacting with one of the clamping members to secure the clamping means to a support, the connecting means
- adjustably secured to the clamping member 30 whereby a line intersecting the axes of the conductors may be varied relatively to the longitudinal axis of the connecting member and means for moving the clamping members into a holding position. 35
15. A support for a pair of conductors comprising a pair of clamping members having oppositely disposed jaws to directly engage and grip one of the conductors and one of the members having a jaw to directly engage and grip the other conductor, and means interposed between the second conductor and the other members to engage the second conductor and coact with the jaw on the first member to grip the second conductor, means on the interposed means engaging means on one of the clamping members whereby the interposed member may be rotated about the second conductor with the axis of the second conductor acting as the 40 center of rotation, means secured to the interposed means for suspending the device from a support and means for securing the clamping members, interposed means and conductors in a fixed relation. 45
- In testimony whereof I affix my signature. 50
- 55

SAMUEL S. MATTHES.
